UNITED STATES PATENT OFFICE.

DAVID E. BOWN, OF CRAFTON, PENNSYLVANIA.

LAMP SOCKET.

1,421,122.

Specification of Letters Patent. Patented June 27, 1922.

Application filed November 5, 1918. Serial No. 261,265.

To all whom it may concern:

Be it known that I, DAVID E. Bown, a resident of Crafton, in the county of Allegheny and State of Pennsylvania, have invented a new and useful Improvement in Lamp Sockets, of which the following is a specification.

This invention relates to sockets for incandescent electric lamps.

10 The object of the invention is to improve the construction of lamp sockets, by simplifying the structure, by reducing the number of insulating parts, by simplifying the method of assembly, and to change the means 15 of connecting and holding the parts together. A further object is to make the parts interchangeable, and to provide a key mechanism allowing the key to be placed in any desired position or adjustment. The 20 radical changes from prior construction and the advantages thereof will be readily apparent to those familiar with the art upon consideration of the following specification.

Referring to the drawings, Fig. 1 is a central vertical section through the socket in assembled position; Fig. 2 is an inverted plan view with the screw shell and outer shell of the socket removed; and Fig. 3 is a partial vertical section of a modification.

30 My construction comprises a cap 1, and outer shell 2, adapted to fit together to form a standard incandescent lamp socket. These parts are made of ordinary sheet metal, mica, porcelain, or composition.

35 The cap has an upward extension 3 through which the conducting wires extend. The cap is formed with a bead 4 about its middle portion. This bead forms an annular groove 5 on the inside of the cap. The lower 40 side 6 of this bead is bent inward at right angles to a cylindrical portion 7 of the cap lying below the bead. The lower side 6 extends inward slightly farther than the upper side of the bead and forms a straight edged 45 shoulder 8. The lower portion of the cap constituting the bead 4 and cylindrical portion 7 is cut into strips, as shown in Fig. 2, for the purpose of permitting ready expansion.

50 The outer shell 2 is formed with an upper enlarged cylindrical portion adapted to fit snugly over the slotted skirt portion 7 of the cap, and with a lower and smaller cylindrical portion adapted to surround the threaded 55 lamp-holding screw shell 9 and an insulating sleeve 10 which covers and protects

the outside of the said screw shell. The upper enlarged cylindrical portion of the outer shell 2 has a longitudinal slot extending from the top to near the lower end of the 60 enlarged portion. This permits the outer shell to be slipped over the lower skirt portion of cap 1; the slot passing around the circular shank 11, of switch key 12.

An insulating body or base member 13 is 65 adapted to form a support for the interior lamp-holding and switch mechanism. This part may be of porcelain, but it is preferred to use a suitable insulating composition in which metal parts may be molded. It comprises a central bore 14, through which conducting wires are led to be attached to terminal binding screws 15 and 16. This insulation piece has a cylindrical body, with an enlarged rounded head 30, which extends 70 upward and outward from the main cylindrical body, forming on its under side a shoulder 17 adapted to seat on the shoulder 8, of the cap, above described.

Molded into the insulating base 13 is a 80 metal strip 18, which extends downward from the bottom of the member 13, forming a rectangular loop in which is rotatably mounted in insulating bushings 33 and 34 the shaft 19 of switch key 12. A contact 85 spring 20 is fastened under the binding post 15 and its free end is positioned so as to be engaged by a rotatable make-and-break conducting contact member 21, mounted on the end of the shaft 19, and adapted in vertical 90 position to connect spring 20 to the upper end 22 of the screw shell 9, as shown in Fig. 1, and in the horizontal position to break the connection between these two parts, in the usual manner. The binding post 16 is attached to an extension 23 of the metal strip 18. In the lower horizontal side of the member 18 is a threaded hole adapted to receive a screw 24, the head of which forms the central terminal contact of the lamp socket. A 95 supplemental washer 25 around the end of the screw 24, may be used if desired. An insulating disc 26 is clamped by the screw 24 between the washer 25 and the member 18.

Between the upper and lower cylindrical 105 portions of the outer shell 2, there is an annular inwardly extending portion 31. The screw shell 9 is formed with an upper flat end wall 22, the central portion of which is cut away to fit around a raised central portion 110 of the insulating member 26, as shown in Fig. 1. Below the end wall 22 is a cylindri-

cal portion 27 fitting around the disc 26, and below this the enlarged threaded lamp-receiving screw shell. This enlargement forms a shoulder 28. An insulating sleeve 10 is formed to fit over the threaded portion, shoulder 28, and cylindrical portion 27, of the screw shell 9.

Assembling the socket is very simple. The supporting metal member 18 is molded 10 into the insulating portion 13. The contact spring 20, and make-and-break switch mechanism are then mounted on this base, which is then forced into the cap 1. The slotted skirt of this cap will readily expand to allow 15 the large head of the insulating base to pass above the shoulder 8 and will then spring back into place, securely holding the base (and the make-and-break mechanism attached thereto) in the cap. Then the insulating sleeve 10 is slipped over the screw shell 9, which is slipped over the insulating disc 26, and these parts are inserted in the outer shell from the lower end thereof, and the shell is telescoped on the skirt of the cap 20 1, thus securely locking the member 13 against removal from the cap. The washer 25 and screw 24 are then put in, and the one screw 24 clamps the cap and shell together, the upper end of the outer shell abutting 25 against the lower side 6 of the bead 4 on the cap, and the shoulder 28 of the screw shell being clamped against the annular internal rib 31 of the cap with the insulating sleeve 10 clamped therebetween.

With this construction it is not necessary 30 to use the ordinary fiber or paper lining in the cap and shell. Also there is a distinct advantage in the method of assembly with this construction, wherein the moving parts 35 are carried by an insulating base which is mounted in the cap, and wherein the cap and base are secured together by a single screw, itself constituting the central terminal socket member.

In Fig. 3 a modification is shown. The insulation body member 13^a extends through 40 the top of the cap 1^a. A spring-ring 32 is seated inside the bead 4^a. When the head of member 13^a is pushed up into the cap, the ring 32 expands into the interior of 45 bead 4^a allowing the shoulder or the body member 13^a to pass above the ring. The latter member then springs together again, locking the base 13^a in position in the cap, as shown.

I claim:

1. A lamp socket comprising a cap and a cooperating outer shell adapted to telescope therewith and having a restricted internal shoulder therein, an insulating member held 50 in the cap, a second insulating member carrying a screw shell, said screw shell being flared outwardly to form an external shoulder adapted to abut the inside of the internal shoulder of the outer shell, an insulating

member positioned to separate the screw shell from the outer shell, a frame member carried by the first mentioned insulating member, and means to clamp the second insulating member to said frame, whereby to 70 hold the cap and shell and associated parts in assembled position.

2. An incandescent lamp socket comprising 75 a cap and outer shell, the cap having an annular shoulder on the inside thereof, an insulating base adapted to be retained in the cap by a shoulder seating on the interior shoulder of the said cap, and a metal conducting member attached to the base and carrying a make-and-break switch mechanism.

3. A lamp socket comprising a metal cap, 80 the cap having an annular bead forming an interior shoulder, the portion of the cap below said shoulder being slit to permit expansion, an insulating base having an enlarged head adapted to be forced into the slotted portion of the cap and to seat above the annular shoulder in the cap, a metal frame member carried by the insulating base and an insulating disc carrying a threaded metal screw shell attached to the lower part of the metal frame member.

4. A lamp socket comprising a metal cap, 85 the cap having an annular bead forming an interior shoulder, the portion of the cap below said shoulder being slit to permit expansion, an insulating base having an enlarged head adapted to be forced into the slotted portion of the cap and to seat above 90 the annular shoulder in the cap, a metal frame member carried by the insulating base having attached thereto a make-and-break switch, and an insulating disc carrying a threaded metal screw shell attached to the lower part of the metal frame member.

5. A lamp socket comprising a cap and outer shell, the cap having an interior bead, 95 a shouldered insulating base and adapted to be inserted in the cap to form a resilient engagement between said bead and shoulder, a metal frame member carried by the base, a make-and-break mechanism, carried by the frame member, an insulating disc carrying a threaded metal screw shell, and a screw 100 adapted to attach the insulating disc to the frame member and to form the central terminal contact member inside the lamp socket.

6. A lamp socket comprising a metal cap, 105 the cap having an annular bead forming an interior shoulder, the portion of the cap below said shoulder being slit to permit expansion, and an insulating base having an enlarged head adapted to be forced into the 110 slotted portion of the cap and to seat above the annular shoulder in the cap.

7. A lamp socket comprising a cap, an outer shell telescoping on a portion of the cap and having an internal shoulder, an in- 115

5. insulating base member engaged by the cap, a metal conducting member attached to the base member and carrying a make-and-break switch mechanism, a screw shell having an external shoulder adapted to abut the shoulder inside the outer shell, an insulating member seated on a shoulder inside the open end of the screw shell, and a screw connecting said latter insulating member to said metal conducting member thereby holding the cap and shell in assembled position.
8. A lamp socket comprising a cap and shell, the cap having an annular interior shoulder adapted to retain an insulating base inserted in the cap, said base carrying binding posts and a make-and-break switch mechanism, and an insulating disc carrying a threaded metal screw shell and surrounding insulating sleeve, said insulating disc being attached to the metal frame by a central terminal contact screw having its head in the screw shell.
9. A lamp socket comprising a cap, an insulating base retained therein, an outer shell having an interior shoulder, a threaded metal screw shell and surrounding insulating sleeve retained in the outer shell and having offset portions abutting the shoulder of the outer shell, an insulating disc in the screw shell, and a central screw adapted to clamp the disc to the base whereby to hold the cap and outer shell together and the screw shell clamped to the outer shell.
10. A lamp socket comprising a cap having an insulating body member locked therein, an outer shell interfitting with the cap, said outer shell having an annular interior bead, a lamp-holding screw shell positioned below said bead, an insulating disc in the screw shell, and a screw extending through the disc into the body member whereby to clamp the cap and shell together and to clamp the screw shell in position inside the outer shell.
11. A lamp socket comprising a metal cap, the cap having an annular bead forming an interior shoulder, the portion of the cap below said shoulder being slit to permit expansion, an insulating base having an enlarged head adapted to be forced into the slotted portion of the cap and to seat above the end of the shoulder in the cap, and a metal shell member adapted to telescope over the slotted portion of the cap to lock the insulating portion therein. 55
12. A lamp socket comprising a cap having an annular bead therein, the portion of the cap beneath said bead being slit to permit expansion, an insulating base member having an annular bead at its top adapted to be forced into the slotted portion of the cap and to seat above the annular bead inside the cap, a metal frame member attached to the lower side of said insulating member, a metal shell member adapted to telescope over the slotted portion of the cap, said metal shell member having an annular interior shoulder, a second insulating member carrying a screw shell, said screw shell having an external shoulder adapted to seat beneath the annular shoulder in the shell, an insulating member positioned between the outer shell and screw shell and means to clamp the second insulating member to the metal frame member attached to the first insulating member. 65
- In testimony whereof I have hereunto set my hand.
- DAVID E. BOWN.
